US00D954576S

(12) **United States Design Patent** (10) Patent No.: **US D954,576 S**
(45) Date of Patent: **** Jun. 14, 2022**

(54) **ELECTRONIC SCALE**

- (71) Applicant: **MIDEA GROUP CO., LTD.**,
Guangdong (CN)
- (72) Inventors: **Jiahong Wang**, Guangdong (CN);
Yuan Yao, Guangdong (CN); **Yangzong Lu**, Guangdong (CN); **Zhuang Li**, Guangdong (CN); **Bowen Yin**, Guangdong (CN)
- (73) Assignee: **MIDEA GROUP CO., LTD.**,
Guangdong (CN)
- (**) Term: **15 Years**
- (21) Appl. No.: **35/511,078**
- (22) Filed: **Oct. 13, 2020**

(80) **Hague Agreement Data**

- Int. Filing Date: **Oct. 13, 2020**
Int. Reg. No.: **DM/211872**
Int. Reg. Date: **Oct. 13, 2020**
Int. Reg. Pub. Date: **Jan. 1, 2021**

(30) **Foreign Application Priority Data**

- Jun. 5, 2020 (CN) 202030279895.3
- (51) LOC (13) Cl. **10-04**
- (52) U.S. Cl. **USPC** **D10/91**
- (58) **Field of Classification Search**
USPC D10/91, 92
CPC G01G 23/00; G01G 23/015; G01G 19/44;
G01G 19/4146

See application file for complete search history.

Primary Examiner — George D. Kirschbaum

(57) **CLAIM**

The ornamental design for an electronic scale, as shown and described.

DESCRIPTION

1. Electronic scale
- 1.1 : Front
- 1.2 : Back
- 1.3 : Left
- 1.4 : Right
- 1.5 : Top
- 1.6 : Bottom
- 1.7 : Perspective
- 1.8 : Perspective view of state of change

1 Claim, 8 Drawing Sheets
